UNITED STATES PATENT OFFICE.

OTHO W. STILES, OF WASHINGTON, DISTRICT OF COLUMBIA.

PEN AND PENCIL ATTACHMENT.

1,310,257.

Specification of Letters Patent. Patented July 15, 1919.

Application filed January 9, 1919. Serial No. 270,403.

To all whom it may concern:

Be it known that I, OTHO W. STILES, a citizen of the United States, residing at Washington, in the District of Columbia, 5 have invented new and useful Improvements in Pen and Pencil Attachments, of which the following is a specification.

This invention relates to improved caps or attachments for pens and pencils, and is 10 particularly adaptable to fountain pens; its primary object being to house in the removable tubular cap of a pen or pencil means for holding an eraser, blade, pencil or other device, and to provide a spring pocket clip 15 having connections therewith, whereby said erasing or other device may be readily thrust out through the end of said cap, or withdrawn therein, and locked automatically in position.

20 Further objects of the present invention are to produce an improved locking arrangement combined with and capable of convenient manipulation by an effective form of spring clip for clasping the hemmed edge of 25 a pocket; to provide for interchanging and renewing the various types of erasers, blades or pencils, which may be employed; to adapt the device to either a removable or fixed tubular cap, or to a tubular extension integral 30 with a penholder or pencil; and to make the improvements readily applicable to existing forms of writing instruments.

Minor objects will become apparent from the following description of preferred forms 35 embodying my invention, reference being had to the accompanying drawings, in which;

Figure 1 is a side elevation of a fountainpen with my invention applied thereto.

40 Fig. 2 is a longitudinal section of the tubular cap and a fragment of the ink reservoir of said pen.

Fig. 3 is a frontal view showing the tubular cap partly broken away to a section 45 on line III—III of Fig. 2.

Fig. 4 is a view of the upper end of the tubular cap.

Fig. 5 is a cross section on line V—V, and 50 Fig. 6 is a cross section on line VI—VI of Fig. 2.

Fig. 7 is a frontal view similar to Fig. 3, being partly broken away to show a steel blade substituted for the wire eraser shown in the latter figure.

55 Fig. 8 is a side view, partly in section, showing the improvements applied to an in-

tegral extension of a pencil casing for adjustable leads.

The reference letter *a* indicates the barrel of a fountain-pen; or the shaft of a pencil 60 or penholder as in Fig. 8, may be substituted therefor; *b* is the pen-point; and *c* designates as an entirety the cap used to cover and protect the pen or pencil point, which is also fitted to receive and engage the tapered upper end of the barrel *a* in the usual or any suitable way. The cap *c* has a tubular body or shell *d* provided with a narrow slot *e* extending longitudinally a considerable distance from its upper end; and 70 said upper end is interiorly slightly beveled or countersunk and exteriorly reduced in diameter and screw-threaded to a shoulder, as shown at *f*. A removable internally threaded end closure *g*, is fitted to be 75 screwed on the terminal threads of the tubular shell *d*, and abut against the shoulder *f*. Said closure *g* has also a circular groove formed in it with a beveled edge *h* adapted to engage the countersunk end of the shell 80 *d* to maintain the tubular form of the latter; and a central aperture *i*, preferably of rectangular form, as shown in Fig. 4, is provided in the closure *g* to permit the passage therethrough of erasing or other means 85 hereinafter described.

A cylindrical body or plunger *j* is slidably fitted to reciprocate within the tubular shell *d*, and has formed in its upper end a central tapped out bore adapted to receive 90 and hold the screw-threaded shank *k* of a blade, eraser, pencil, or other device designated generically by the reference letter *l*. The cap *c* and plunger *j* may be of hard rubber, metal, or any suitable material, but 95 the shank *k* should be metallic, as also are the casings of the erasers *l* shown in Figs. 2, 3, 4 and 8, and the steel blade *l* of Fig. 7.

In Figs. 2, 3 and 4 is shown at *l* a form of the well known wire brush eraser, being a 100 fagot of small tempered steel wires *m* secured at one end in a tubular holder *n* telescoped into an outer tube *o*, and held in position by a clamping screw *p* slideable throughout a longitudinal slot *q* in the tube *o*. It is 105 obvious that an eraser of rubber or composition material may be substituted for the fagot *m* in the same or an analogous arrangement such as indicated in Fig. 8. In Fig. 7 a steel blade for erasing or cutting is shown 110 at *l*; or a small lead pencil may be substituted; and these various forms of *l* may be

readily interchanged after removing the end closure *g*.

A flat metal leaf spring *s* with a U-shaped bend has its inner leg provided with lateral ears *n* and concaved to fit the curvature of the cap *c*, being disposed longitudinally thereof, and secured to the plunger *j* by suitable means such as a screw *t* which may slide in the cap slot *e*. The outer leg of the spring *s* is sprung back against the cap *c*, at a point below the termination of the inner leg, and has its end slightly bent outward and shaped as at *u* to form a spring clip adapted to slip over and clamp the hem of a pocket against the cap *c*.

A deep rectangular groove or indentation *v* is cut laterally across the plunger *j* near its lower end; and a lock-bolt head *w* is slidably fitted therein, being provided with a stem *y* 20 slidable in the cap slot *e*. The stem *y* projects outward through an aperture *z* in the inner leg of the spring *s*, and its termination is secured by riveting or otherwise to the outer leg of the spring *s* about midway of the length of the latter, as shown at 2. The bolt head *w* is rectangular, except as to its outer face which is curved concentrically with the plunger *j*. A plurality of pairs of recesses *3* are sunk in the interior surface of 25 the tube *d* athwart the slot *e* and each pair is adapted to receive the outer end of the bolt head *w* so as to prevent movement of the plunger *j*. Only two pairs of locking sockets or recesses *3* are shown herein, but it is 30 evident that more may be provided if desired.

While I prefer to incorporate the device with a removable cap *c* in all cases, yet it may be desired to embody the invention, as 40 shown in Fig. 8, with an extension *d* of the shaft or barrel *a* of a pencil or pen. This construction is best adapted to pencils for holding and adjusting a bare lead *4*, as shown; and the arrangement is similar in 45 other respects to that above described.

It should now be apparent that the erasing or other device *l* is normally housed within the tube *d*, being locked therein because of the retention by the spring *s* of the bolt-head *w* in engagement with the lower pair of 50 registering recesses *3*; and springing the clip *u* over the hem of a pocket locks the said parts together even more rigidly. The device is quickly and conveniently made ready 55 for use, however, a slight pressure of the operator's thumb upon the outer leg of the spring *s* in the vicinity of the point 2 serves to release the head *w* from the sockets *3*, whereupon a forward thrust of the thumb 60 slides the said spring, together with the plunger *j* and its device *l*, to the operative position, as shown by the dotted lines and arrows in Fig. 2. In this position for use the device *l* projects outside of and is 65 steadied by the walls of the cap aperture *i*,

and releasing the thumb pressure permits the head *w* to spring outward into the upper pair of sockets *3*, or into any other pair of such sockets that may be provided, which prevents both longitudinal and rotary movement of the device *l*.

Substantially the same simple operation with a withdrawal of the thumb returns the device *l* and locks it within the tube *d*.

I further point out and distinctly claim as my invention:—

1. In a device of the class described, a tube having a longitudinal slot therein, a tool-holding plunger slidable in said tube, a spring rigidly connected through said slot 80 with said plunger and adapted to ride on the exterior of said tube, and means operative by said spring for locking said plunger to said tube.

2. In a device of the class described, a 85 tube having a longitudinal slot therein, a tool-holding plunger slidable in said tube, a spring member located exteriorly of said tube and rigidly secured to said plunger by a connection slidable in said slot, a bent 90 part of said spring member terminating in a pocket clip, and means whereby the bent part of said spring member operates normally to lock said plunger to said tube.

3. In a device of the class described, a 95 tube having a longitudinal slot therein, a tool-holding plunger slidable in said tube and provided with a groove formed laterally across it, a spring pocket clip member adapted to ride on the outside of said tube, 100 said member being secured to said plunger by connecting means passing through said slot, and means slidable in said groove and operatively connected with said pocket clip member for locking said plunger to said 105 tube.

4. In a device of the class described, a tube having a longitudinal slot therein, a plunger slidable in said tube provided with means for holding a tool, a bent spring having its inner leg adapted to ride on the exterior of said tube and rigidly connected through said slot with said plunger, the outer leg of said spring overhanging the end of its inner leg and terminating in contact 115 with said tube, and means operatively connected with the outer leg of said spring for locking said plunger to said tube.

5. The combination with a writing instrument, of a tubular cap therefor provided with a longitudinal slot, a tool-holding plunger slidable in said cap and having a recess in its side, a spring located exteriorly of said cap and rigidly connected through said slot with said plunger, a bent part of 125 said spring terminating in a pocket clip bearing against said cap, a locking member fitted to slide in the recess in said plunger, and connecting means whereby said locking member is normally held in engagement 130

with said cap by the resilient force of the bent part of said spring.

6. The combination with a writing instrument, of a tubular cap therefor having a longitudinal slot therein and provided with a plurality of interior sockets disposed in pairs on opposite sides of said slot, a tool-holding plunger adapted to reciprocate in said cap and having a parallel-walled recess in its side, a spring located exteriorly of said cap and rigidly connected through said slot with said plunger, a bent over part of said spring terminating in a pocket clip bearing against said cap, a locking bolt having its head fitted to slide in the recess in said plunger and engage the interior sockets of said cap, and a stem of said locking bolt leading out through the slot in said cap and terminally secured to the bent over part of said spring.

7. The combination with a writing instrument, of a longitudinally slotted tube, a plunger adapted to reciprocate in said tube, a spring member fitted to ride on the outside of said tube and fixedly secured to said plunger, means operative by said spring member for locking said plunger to said tube, an implement attached to the upper end of said plunger, and a closure for the upper end of said tube provided with an aperture through which said implement may pass.

In testimony whereof I affix my signature in the presence of two subscribing witnesses, at Washington, D. C., this 9th day of January, 1919.

OTHO W. STILES.
